Primary Examiner—Terry A. Wallace[57] **CLAIM**

The ornamental design for a crusher, as shown and described.

DESCRIPTION

FIG. 1 is a perspective from the right top of the crusher

consisting of an upper crusher member and a lower crusher member joined in a pivotal relationship by a pivot pin embodying the features of my new design;

FIG. 2 is a front elevation of the upper crusher member thereof;

FIG. 3 is a rear elevation of the upper crusher member thereof;

FIG. 4 is a right side elevation of the upper crusher member, the left side elevation of the upper crusher member being a mirror image of the right side elevation of the upper crusher member, thereof;

FIG. 5 is a bottom elevation of the upper crusher member thereof;

FIG. 6 is a bottom elevation of the lower crusher member thereof;

FIG. 7 is a front elevation of the lower crusher member thereof;

FIG. 8 is a rear elevation of the lower crusher member thereof;

FIG. 9 is a right side elevation of the lower crusher member, the left side elevation of the lower crusher member being a mirror image of the right side elevation of the lower crusher member, thereof;

FIG. 10 is a top elevation of the lower crusher member thereof;

FIG. 11 is a bottom elevation of the lower crusher member thereof; and,

FIG. 12 is a perspective view of the pivot pin thereof.
